US0D1013579S

(12) **United States Design Patent** (10) Patent No.: **US D1,013,579 S**
(45) Date of Patent: ** Feb. 6, 2024

(54) **TRAILER REAR IMPACT GUARD**

(71) Applicant: **STI Holdings, Inc.**, Stoughton, WI (US)

(72) Inventors: **Daniel Patrick Miller**, Madison, WI (US); **Francis Steven Smidler**, Stoughton, WI (US)

(73) Assignee: **STI Holdings, Inc.**, Stoughton, WI (US)

(**) Term: **15 Years**

(21) Appl. No.: **29/740,628**

(22) Filed: **Jul. 6, 2020**

Related U.S. Application Data

(63) Continuation of application No. 29/705,836, filed on Sep. 16, 2019, now Pat. No. Des. 889,320, which is a continuation of application No. 29/607,993, filed on Jun. 19, 2017, now Pat. No. Des. 864,038, which is a continuation of application No. 29/529,050, filed on Jun. 3, 2015, now Pat. No. Des. 790,407.

(57) **CLAIM**

We claim the ornamental design for a trailer rear impact guard, as shown and described.

DESCRIPTION

The sole FIGURE shows a rear view of a trailer rear impact guard showing our new design.

The portions of the design shown in broken lines disclose environmental structure and form no part of the claimed design.

1 Claim, 1 Drawing Sheet
